(57) CLAIM

The ornamental design for a combined cigar case with ashtray, as shown and described.

DESCRIPTION

FIG. 1 is a front and top perspective view of a combined cigar case with ashtray, showing my new design;

FIG. 2 is a rear and bottom perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is another perspective view thereof, shown in an alternative position; and,

FIG. 10 is an enlarged perspective view of detail “10” identified in FIG. 1.

The broken lines consisting of evenly spaced dash lines in the drawings depict portions of the combined cigar case with ashtray that form no part of the claimed design; The broken lines consisting of short and long dash lines encircling the enlarged detail views in FIGS. 1 and 10 are for annotative purposes and form no part of the claimed design.
